UNITED STATES PATENT OFFICE.

HENRY ADAMS, OF STAMFORD, CONNECTICUT, ASSIGNOR TO THE ADAMS MINING MACHINERY CORPORATION, OF NEW LONDON, CONNECTICUT, A CORPORATION OF NEW YORK.

PROCESS AND APPARATUS FOR REDUCING COAL.

1,293,654.

Specification of Letters Patent. Patented Feb. 11, 1919.

Application filed August 24, 1915. Serial No. 47,064.

To all whom it may concern:

Be it known that I, HENRY ADAMS, a citizen of the United States, and a resident of Stamford, county of Fairfield, and State 5 of Connecticut, have invented certain new and useful Improvements in Processes and Apparatus for Reducing Coal, of which the following is a specification, reference being had to the accompanying drawings, which 10 form a part hereof.

This invention relates to a new and improved process and apparatus for reducing coal as it comes from the mine into commercial sizes, and also for grading the coal 15 thus reduced and separating it into the various commercial sizes and for removing impurities therefrom.

According to the process heretofore in vogue for reducing coal into commercial 20 sizes the coal, in mined sizes, is passed through a breaker provided with crushing rolls between which the coal passes and is reduced by the crushing power of the rolls. The crusher is generally a complicated machine and is costly to install and operate. 25 Moreover, its action upon the coal is attended with a number of disadvantages.

In the first place its action cannot be controlled so as to produce at will a reasonably 30 fixed proportion of particular sizes of coal to suit market demands. Consequently, there is often an over production of a size or sizes for which there is no ready market, and storage and extra handling of such excess product is necessary. This entails an 35 added expense. There appears, also, to be a growing demand for steam sizes and a diminishing demand for larger sizes, such as egg, and it would, therefore, be desirable 40 to reduce the egg so as to obtain from it an increased amount of steam sizes if this could be done economically. Such economic reduction would be accomplished if, in reducing the egg to obtain the steam sizes 45 a suitable proportion of stove and nut sizes could also be produced, the higher prices realized for these latter sizes compensating for the lower prices realized for the steam sizes. But the crusher, heretofore in general 50 use, does not reliably lend itself to such economic reduction because of the excess

production of the steam sizes and the small production of stove and nut sizes by the crusher when reducing the egg size.

Again, inspection of coal that has been 55 broken in a crusher will show that the crusher has left in the pieces of coal many minute fractures, probably due to the action of the rolls in exerting pressure on opposite sides of the lumps of coal. As a consequence 60 of this, a crumbling of the coal and a resulting degradation in size of such coal is produced in the subsequent handling and shipment of the coal accompanied by a production of fines and waste that is most undesirable 65 and represents a substantial loss in the caloric value of the product. This crumbling of crusher reduced coal with its attendant loss is well recognized and cannot be overcome or effectively diminished, although 70 effort is sometimes made to lessen it by handling the coal as few times as possible in its journey from the crusher to the furnace.

Furthermore, in the production of steam 75 sizes of coal, buckwheat and smaller, in a crusher it will be found that a large proportion of the pieces, sometimes as high as seventy-five per cent. are flat or nearly so. In a bed of such coal the pieces pack closely 80 together and so provide voids or spaces between the pieces that are insufficient in amount to permit ready combustion without forced draft. When such coal is burned in a furnace a forced draft created by some 85 mechanical means is therefore required to drive the air in sufficient quantity through the bed of coal.

In the applicant's process, the objections noted in the foregoing are obviated or overcome to a substantial degree. In accordance 90 with the applicant's invention the crusher of the prior art with its crushing rolls is not used at all. The coal, in lump or a smaller size, is caused to fly at high speed against a 95 breaking face whereby the coal is broken or shattered into smaller pieces of varying sizes. The coal thus broken is caused to travel from the breaking face substantially free from pulverizing or breaking concussion and attrition between the largest and 100 the smaller broken pieces and to separate

into gradations. If such separation into gradations is not sufficiently complete for commercial purposes, further separation into the various commercial sizes may be 5 made, and if the largest size of the broken coal is too large for the market it may be subjected to another breaking operation, as in a second apparatus. Coal broken in the manner described is remarkably free from 10 the internal fractures that characterize coal that has been reduced in a crusher. The sudden violent blow imparted to the lumps of coal by the breaking face against which they are hurled shatters them into fragments or 15 pieces but in large measure leaves the broken pieces free from these internal fractures and structurally strong. This coal may, therefore, be handled and shipped without suffering any such degradation of size and loss as 20 is suffered by crusher reduced coal under like circumstances.

Moreover, in reducing coal in accordance with the present invention there is a very noticeable absence of flatness in the steam 25 sizes as compared with coal of corresponding sizes produced in a crusher, so that in the former the voids are increased some three and a half per cent. This is an important advantage because it substantially facilitates the passage of air through the bed 30 of such coal in the furnace and obviates or reduces the need of forced draft.

Furthermore, in carrying out the process 35 of the present invention it is possible to control to a substantial degree the production of the smaller sizes. This may be done by increasing or decreasing the force with which the coal is hurled against the breaking face. The greater this force is, within limits 40 of its, the greater is the proportion of the smaller sizes produced. One convenient way of bringing about the desired result is to increase or decrease the speed of the centrifugal table employed as the projector to 45 hurl the coal against the breaking face. Another way is to increase or decrease the distance between the periphery of the centrifugal table and the breaking face spaced apart therefrom, the momentum of the coal decreasing as this distance is increased. The 50 breaking face is preferably provided with a multiplicity of pins or studs against which the lumps of coal impinge. Reducing the number of these studs also reduces the proportion 55 of the smaller sizes of coal produced.

The process may be carried out by various forms of apparatus. In the accompanying drawings are shown the preferred form of apparatus with two modifications, such 60 apparatus constituting part of the present invention.

Figure 1 is a plan view of the preferred form of apparatus.

Fig. 2 is a central sectional elevation 65 thereof.

Fig. 3 is a diagrammatic representation in sectional elevation showing a separator and gravity picker.

Fig. 4 is a side elevation of the structure shown in Fig. 1 looking toward the left. 70

Figs. 5 and 6 are central sectional elevations showing modified forms of apparatus.

Fig. 7 is a fragmental plan view of the apparatus shown in Fig. 6.

Referring now more particularly to the 75 structure as shown in Figs. 1 to 4 inclusive, 1 is a rotating or centrifugal table carried on the vertical shaft 2 which is supported in suitable bearings. This shaft is driven by convenient means such as the electric motor 80 3 suitably connected with the shaft 2, as through the belt 4 and bevel gear wheels 5 and 6, the wheel 6 being fixed on the shaft 2 and the wheel 5 being fixed on a transverse shaft driven by the belt 4. The table 1 is 85 provided with a plurality of radial wings 7 which, in the present instance, are seven in number. The coal to be operated upon is delivered centrally to the table from the hopper 8.

Spaced apart from the table 1 and surrounding the table is a breaking face for shattering or breaking the coal. In the present instance, this breaking face comprises a series of anvils 9 which rest upon a 90 base 10 supported on angle beams, such as 11 and 12, carried by pillars, such as 13 and 14. The anvils may be provided with strengthening ribs 44. In the front or vertical faces of each of the anvils 9 are fixed 100 a series of pins or studs 15. These are shown in the drawings as being threaded so as to screw into place and be separately removable either for repair or for varying the number of studs in the breaking face. Beneath the anvils 9 and suitably supported is an inverted conical screen 16 which is made up of a series of rods connected together by two transverse tie rods 17. This screen may be variously constructed but its purpose is 110 to receive the broken coal as it travels from the anvils, carrying the largest broken pieces to a central hopper 18 and permitting the smaller broken pieces to pass through the screen and thereby immediately separate 115 from these largest broken pieces. 19, 20, 21, 22 and 23 are a series of guides which partly surround the screen 16 on one side and extend outward and downward therefrom. These guides receive the broken coal as it 120 passes through the screen 16 and conduct it to a shaking separator 24. A similar set of guides 25, 26, 27, 28 and 29 is arranged on the opposite side of the screen 16 so that all the broken coal passing through the screen 125 falls on to the guides. These guides may vary in number but it is preferable to use several in order to divide the coal into several streams as it falls from the screen 16, thereby reducing attrition between the 130

broken pieces of coal. 30, 31 and 32 are conveyer belts to carry the broken coal from the guides 25—29 to the shaking separator 24.

This shaking separator 24 may be actuated by any suitable means as, for example, the cam 33 and belt 34 driven by the electric motor 3 as indicated in the drawings. The coal is separated into its varying sizes by means of the shaking separator 24, the fines and dust passing through the separator to a conveyer 35 which leads to the culm bank. The coal in its separated sizes is delivered from the separator 24 to a gravity picker 36 of any well known type whereby the heavier impurities, such as slate, bone and rock, are removed from the coal. These impurities are carried away by conveyers such as 37 and 38, the coal in its separated sizes being delivered by the gravity picker to conveyers, such as 39 and 40.

41 is a cover for the anvils. 42 is a controller for the motor 3 by means of which the speed of the table 1 may be regulated. 43 is a conveyer to receive from the hopper 18 the coal delivered thereto.

In the operation of the machine the coal in lump or smaller size is delivered from the hopper 8 on to the rotating table 1 where it is caught by the wings 7 and carried around with the table. The centrifugal force thus imparted to the coal throws it outward with great force against the breaking face whereby it is broken into smaller pieces of varying sizes. These broken pieces then fall upon the screen 16, the largest of such pieces traveling down the screen to the hopper 18 which delivers them to the conveyer 43. The smaller broken pieces travel to and through the screen 16 on to the guides 19, etc., and 25, etc., from which they are delivered to the shaking separator 24 for separation thereby into various commercial sizes and subsequent delivery to the gravity picker 36 whence they are delivered to the conveyers 39, 40 etc. If the coal delivered to the conveyer 43 requires further reduction, it may be fed to another machine and reduced to smaller sizes in a similar manner.

In reducing the coal in the manner described in the foregoing, the large pieces of coal fly with great speed against the breaking face and the broken pieces travel with great speed to the screen 16 through which or down which they pass. In this movement the coal is substantially free from pulverizing and breaking concussion and attrition between the largest and the smaller broken pieces and waste is reduced to a minimum.

While a centrifugal table, as shown, is preferred as the best type of projector for imparting movement to the coal in its travel against the breaking face, the process may be carried out in connection with other types

of projector or the coal may even be dropped from a suitable height upon a breaking face of appropriate construction and arrangement.

By varying the speed of the centrifugal table, the impact of the coal against the breaking face may be regulated. This controls the amount of smaller sizes produced. The amount of the smaller sizes produced may be diminished by removing some of the 75 studs in the anvils and may also be diminished by increasing the distance between the breaking face and the periphery of the centrifugal table. The anvils are separately movable and, if desired, they may be moved 80 farther away from the table and one or more anvils added to the ring which they form. This would diminish the breaking impact of the coal.

In the modification shown in Fig. 5, the 85 general arrangement is similar to that shown in Figs. 1 and 2 but in Fig. 5 the table 45 has a conical upper surface and there is a difference in the construction of the anvils and in the arrangement of some 90 of the guides. In Fig. 5 the anvils 46 are pierced with holes 47 through which much of the smaller sizes of broken coal may pass to guides 48, 49 and 50 and guides 51, 52 and 53, whereby they are delivered, as before, to the shaking separator 24. 54, 55, 56 and 57 are guides for delivering the smaller broken pieces that fall upon and pass through the screen 58 either directly to the separator 24 or to conveyers which deliver 100 them to said separator.

In the modification shown in Figs. 6 and 7 the anvils 59 are similar to those shown in Figs. 1 and 2 but there is a difference in the construction and arrangement of the 105 centrifugal table and no screen is employed such as the screen 16. In Figs. 6 and 7 the centrifugal table 60 is provided with openings or slots 61 near its periphery and the edge of the table extends close to the anvils 110 59. The table is provided with wings similar to the wings 7 of table 1. The coal is fed to the table, not centrally as in Figs. 1 and 2, but at two points on opposite sides of the center through the hopper 62 and its outlets 63 and 64. As the broken coal rebounds from the anvils it falls upon the table and the smaller pieces pass through the slots 61 and out along the guides 65, 66, 67 and 68 by which it is conducted directly 115 or through conveyers, such as the conveyer 69, to the shaking separator 24 and then to a gravity picker. The pieces of broken coal which the anvils have failed to break into pieces sufficiently small to pass through the slots 61 are again hurled by the table 120 against the anvils and broken into smaller pieces which are able to pass through the slots of the table when they rebound from the anvils. The feed of the coal to the 125

130

table 60 at two opposite points through the outlets 63 and 64 is provided in order that the coal passing on to the table and thence against the anvils may not interfere with 5 the broken coal rebounding from the anvils to the table.

What I claim is:

1. A process for reducing coal to different sizes consisting in centrifugally 10 breaking lumps of coal against an impact surface; returning by impact action oversized lumps to be rebroken; directly discharging by impact action the under size pieces and assorting said undersize pieces 15 to the desired sizes during a continuous operation.
2. In an apparatus for reducing coal to commercial sizes, the combination of a cir-

cular centrifugal table having radial arms thereon adapted to project lumps of coal therefrom; means for feeding coal to said table; an annular breaking anvil surrounding said table and spaced therefrom to provide a space through which may fall large and small pieces of coal; an inverted conical screen disposed with its peripheral portions extending to said anvil, and comprising a plurality of rods converging toward each other and terminating a distance from the axis of the cone; and concentric guides disposed beneath said screen and coaxial therewith.

This specification signed this 19th day of August A. D. 1915.

HENRY ADAMS.
